UNITED STATES PATENT OFFICE

CHARLES L. BRADEMAYER AND CLAUDE L. KOONCE, OF COLEMAN, FLORIDA

WIRE FASTENER FOR FRUIT AND VEGETABLE CONTAINERS

Application filed November 16, 1929. Serial No. 407,742.

The invention relates to a wire fastener for containers for fruits, vegetables, and the like.

The object of the present invention is to provide for containers such as slatted baskets,

5 barrels, and the like, for fruit, vegetables, and similar commodities, a simple, practical and efficient wire fastener of strong, durable and comparatively inexpensive construction adapted to be applied with mathematical 10 accuracy at the factory where such containers are constructed to enable two diametrically arranged wires to be accurately crossed over the top or cover of the container, so that the top will be held tightly in its closed position 15 without liability of spilling or bruising any of the contents of the container.

Heretofore in the shipment of fruits, vegetables, and the like in slatted baskets or similar receptacles, it has been the practice to

20 secure the ends of such crossed wires by twisting them around the top hoop, but, as is often the case, the openings between the slats do not occur at exactly diametrically opposite points, and the wires cannot be 25 accurately crossed in the center of the top of the container, and the top is more or less loose and shaky. Also, it is almost impossible to draw the wire sufficiently tight around the wooden top hoop of the container and twist

30 it so as to hold the top perfectly tight, and in practice there has been more or less slack of the wire, which results in a loose top with liability of loss of the contents when peas or other small products are shipped, while the 35 wire twisted in this manner often results in bruising the contents when larger products such as cucumbers, squash, and the like, are shipped.

Furthermore, considerable time is required 40 in fastening the wires around the top hoop and considerable time is lost in opening the container for inspection, which is now generally required in certain sections of the country since the advent of the Mediterranean fly.

45 It is also an object of the invention to eliminate the foregoing difficulties and objections and to provide a fastener which will enable the crossed wires to be drawn perfectly tight and quickly and securely fastened and un- 50 fastened without liability of kinking the

wires, which almost invariably results when wires twisted around the top hoop are fastened and unfastened.

With these and other objects in view, the invention consists in the construction and 55 novel combination and arrangement of parts hereinafter described, illustrated in the accompanying drawings, and set forth in the claims hereto appended, it being understood that various changes in the form, proportion, 60 and minor details of construction, within the scope of the claims, may be resorted to without departing from the spirit of the invention, or sacrificing any of the advantages thereof. 65

In the drawings:

Figure 1 is a plan view of a container provided with wire fasteners constructed in accordance with this invention.

Fig. 2 is an enlarged side elevation of a 70 portion of the container.

Fig. 3 is a vertical sectional view through the center of the fastener.

Fig. 4 is a detail sectional view taken at right angles to Fig. 3, illustrating the manner 75 of fastening the wire.

Fig. 5 is a plan view of a blank from which the fastener is formed when constructed of malleable metal.

In the accompanying drawings, in which 80 is illustrated the preferred embodiment of the invention, 1 designates the body of a container having a removable top 2 which is secured to the body by diametrically arranged wires 3 which cross the top of the container 85 at the center of the top, as clearly illustrated in Fig. 1 of the drawing. The wires are accurately arranged with relation to the top of the container in order to hold the latter firmly in its closed position upon the body 90 of the container, which is provided at diametrically opposite points with four wire fasteners, each consisting of an attaching plate 4, an outer upwardly extending flange or tongue 5 and a connecting bottom portion 6. The wire fastener is constructed of suitable metal and it may be formed of malleable metal and consists of a blank 7 bent transversely at the bottom connecting portion to 95 form the inner attaching plate and the outer 100

flange or tongue, which is supported in slightly spaced relation to the attaching plate by the bottom connecting portion 6. The attaching plate is preferably tapered and approximately triangular, as clearly illustrated in Figs. 2 and 3 of the drawing, and it is secured to the top hoop 8 or other suitable portion of a container by means of suitable fastening devices 9, which pierce the plate adjacent the bottom thereof at opposite sides of the tongue or flange. Any number of fastening devices may, of course, be employed, but the two fastening devices located at the bottom of the fastener at opposite sides thereof will be ample.

The bottom connecting portion 6 is provided with a central wire receiving opening 10 and the flange or tongue is approximately inverted heart shaped to form laterally extending lobes 11 which provide bottom shoulders at opposite sides of the lower end of the tongue or flange. The end portion 12 of the wire is drawn downwardly over the upper edge of the top hoop and is passed through the central perforation or opening in the bottom of the fastener and is twisted around the bottom connection portion of the fastener by being bent horizontally and laterally in one direction and then upwardly and horizontally over the upper face of the bottom connecting portion, and then downwardly at the opposite end thereof. This will be sufficient to positively secure the end of the wire to the fastener, which will enable the end of the wire to be quickly and securely attached to the body of the container and rapidly unfastened therefrom, and the drawing of the wire through the wire-receiving opening will straighten the wire and remove kinks therefrom, so that when the wire is refastened, it may be drawn perfectly taut without liability of kinks forming in the wire and afterwards resulting in a loosening of the top of the container.

In practice, one end of each wire will be secured to one of the wire fasteners, leaving the other end of each wire free for the application of the cover to the container. After the container is filled, the top or cover is placed thereon and the wires secured to the fasteners, which will enable the wires secured to the remaining to be drawn taut, as will be readily understood.

What is claimed is:

1. A wire fastener for containers of the class described, comprising an attaching plate adapted to be secured to the body of the container, an outer tongue and a bottom portion connecting the attaching plate and the tongue and being of a length less than the width of the tongue to form bottom shoulders, said bottom connecting portion being provided with a central wire receiving opening adapted to permit a wire to be passed through

it and to be twisted around the bottom connecting portion of the fastener.

2. A wire fastener for containers of the class described, comprising an attaching plate adapted to be secured to the body of a container, an outer flange or tongue having laterally projecting lobes forming bottom shoulders, and a bottom portion connecting the attaching plate and the flange or tongue, and provided with a wire receiving opening, said bottom portion offsetting the outer tongue or flange from the attaching plate to permit a wire to be bent around the said outer tongue or flange below the shoulders thereof.

3. The combination with a container having a body portion and a removable top and wires extending diametrically across the top of the container and crossed at the center thereof, of wire fasteners located at diametrically opposite points on the body of the container and comprising an attaching plate secured to the body of the container, an outer upwardly extending flange or tongue and a bottom connecting portion of a length less than the width of the tongue at the bottom thereof to form opposite shoulders, said bottom portion being provided with a wire receiving aperture adapted to receive the end portion of the wire and to permit the same to be twisted around the bottom portion between the shoulders of the outer flange or tongue and operable to straighten the wire when drawing it through the said aperture.

In testimony whereof we affix our signatures.

CHARLES L. BRADEMEYER.
